UNITED STATES PATENT OFFICE.

LANSING PORTER, OF AUBURN, NEW YORK.

CAR-JOURNAL BEARING.

SPECIFICATION forming part of Letters Patent No. 495,188, dated April 11, 1893.

Application filed March 3, 1892. Serial No. 423,625. (No model.)

To all whom it may concern.

Be it known that I, LANSING PORTER, of Auburn, in the county of Cayuga and State of New York, have invented certain new and useful Improvements in Journal-Bearings; and I do hereby declare the following to be a full, clear, and exact description of the invention, such as will enable others skilled in the art to which it appertains to make and use the same.

My invention relates to an improvement in journal bearings, the object being to provide bearings for supporting the axles of railroad cars and the shafting of other movable parts of machinery which will theoretically be free from friction.

With this end in view my invention consists in the parts and combinations of parts as will be hereinafter more fully described and pointed out in the claims.

It is evident that my invention is applicable for use on shafting or other movable parts of machinery, but for convenience, I have illustrated it in connection with the axle of a railroad car.

In the accompanying drawings, Figure 1 is a plan view. Fig. 2 is an end view. Fig. 3 is a longitudinal sectional view of my invention, and Fig. 4 is a sectional view on line 30 $x-x$ of Fig. 3.

A represents a car wheel and B the axle thereof supported at its ends in bearings to be hereinafter described. As the bearings supporting both ends are alike, a description 35 of one will be sufficient.

On the trucks of railroad cars, pressure and friction in three directions are to be guarded against. First, and the most important is the vertical pressure downward from the superincumbent weight; second, the pressure and friction forward and backward, caused by starting and stopping, by running grades, and by the application of the brakes, and the third is the lateral pressure and friction 40 caused by curves and switches. I have provided devices for reducing to a minimum the friction of the parts in the three directions above referred to and will refer to them in the order in which they are stated above.

50 The superincumbent weight rests on a horizontal plate C, rigidly secured in any desired manner to the truck. This plate rests upon

a nest of cone-shaped rollers D D', suitably mounted in a circular groove a formed in the top face of the revolving disk E. The groove 55 a in which these rollers run is so formed that the upper surfaces of rollers D are in a horizontal plane to engage the horizontal under face of the plate C. This revolving disk which sustains the weight rests in turn over 60 and in contact with the revolving axle B. This structure supports the weight and supplies the axle with an endless horizontal movable plane upon which it runs. The great pressure between the axle and the disk E 65 would be sufficient to compel continuous revolution of the disk, but I prefer to impart a positive rotation to the disk by means of semi-spherical projections b engaging correspondingly shaped recesses in the axle. 70

The parts above described support the superincumbent weight while the parts now to be referred to, take up or absorb to a large extent the backward and forward friction caused by starting stopping, &c. The axle B 75 passes through chamber F in truck frame, the vertical diameter of said chamber or box being slightly greater than its horizontal diameter, which permits the cylindrical rollers D², D³ to pass over the top of the axle without 80 any pressure, or in other words the chamber or box is prevented from bearing any of the incumbent weight, and is not allowed to carry any part of the weight to the part of the axle that is directly underneath it, the said rollers 85 being in contact with the axle only in front and back and take the pressure in those directions. When two loaded rollers are traveling in the same direction, their adjacent sides move in different directions, that is to 90 say the back face of the forward roller is moving upward, and the front face of the back roller in contact with it is moving downward. This results in friction, wear and impeded movement. In my device the alternate rollers D' and D³ are slightly less in diameter 95 than the rollers D, D² in order that they may be entirely relieved from vertical pressure, while the larger rollers D D² are the burden bearers and the smaller rollers D' and D³ being pressed between the burden bearers are 100 at liberty to revolve backward while actually traveling forward, thereby theoretically removing all friction in the entire nest of roll-

ers. These rollers D²D³ are supported against endwise displacement, but as before stated are allowed to travel with the axle.

The third direction of pressure is the lateral or endwise pressure of the axle, caused by curves and switches. To overcome this I provide the axle B with a shoulder, or collar G, the outer surface of which is in a plane slightly outside the journal bearing, so as to rest solidly against and move with the periphery of the revolving disk E. By this arrangement both faces at the point of contact are in motion in the same direction. The bolt I carrying the disk E is what eventually receives this lateral or endwise pressure, and is about the only stationary part to cause friction in the entire arrangement and it is evident here that the friction at this point can be reduced to a minimum by the introduction of ball or roller bearings around the bolt I. This bolt passes through plate C and is supported at a point below the disk E in the bracket I'.

While I have described my improvement in connection with a car axle I would have it understood that I do not limit its application to such a device, nor do I confine myself to the details of construction herein disclosed, as it is evident that the device can be applied with equal success to shafting and other parts of machinery and that the details can be varied without departing from the spirit of my invention.

Having fully described my invention, what I claim as new, and desire to secure by Letters Patent, is—

1. In a journal bearing for railway trucks, the combination with an axle and a truck frame, of a revolving disk carried by the truck frame and resting above and in contact with the axle, the said disk having a flat horizontal surface for contact with a cylindrical surface on the axle, substantially as set forth.

2. In a journal bearing, the combination with a revolving shaft or like object and a rotating disk adapted to support the weight carried by said shaft, and be moved by contact with said shaft, the said disk having a flat face adapted to move in contact with a cylindrical surface on the shaft, of roller bearings surrounding the shaft the said roller bearings supporting said shaft on its front and rear sides only, substantially as set forth.

3. In a journal bearing the combination

with a revolving shaft or like object, and a rotary disk moving in contact with said shaft 55 and adapted to support the weight carried by said shaft of a box through which the shaft passes, the vertical diameter of the box being greater than its horizontal diameter and rollers in said box, the said rollers being of such 60 size relative to the shaft and horizontal diameter of the box that they hold the shaft against forward or backward movement, substantially as set forth.

4. In a journal bearing the combination 65 with a revolving shaft or like object having a shoulder or collar thereon, of a movable horizontal disk adapted to support the weight carried by said shaft and be moved by contact with a cylindrical body or surface on said 70 shaft, and anti-friction rollers carried by said disk and bearing against a stationary support, the said shoulder or collar on the shaft resting in contact with the periphery of the revolving disk, substantially as set forth. 75

5. In a journal bearing the combination with a shaft or like object having a shoulder or collar thereon, and a box and anti-friction rollers located within the box and surrounding the shaft, of a revolving disk adapted to 80 support the weight carried by the shaft the said disk bearing at its periphery against the shoulder or collar, substantially as set forth.

6. The combination with a plate or support, a revolving disk located below same and anti- 85 friction rollers between said disk and plate, of an axle one end of which rests against the underside of the revolving disk with its shoulder or collar in contact with said disk.

7. The combination of a stationary part, a 90 movable part mounted on a centrally located axis a series of rollers of equal diameter loosely nested between the movable and stationary parts, a series of rollers of smaller diameter than the first mentioned rollers, and alternating with said first mentioned rollers, and a revolving shaft or like object having direct contact with said movable part, substantially as set forth. 95

In testimony whereof I have signed this 100 specification in the presence of two subscribing witnesses.

LANSING PORTER.
